DESIGN FOR A TUMBLER

Albert S. Eggleton, Big Flats, N. Y., assignor to Corning Glass Works, Corning N. Y., a corporation of New York

Application March 5, 1941, Serial No. 99,368

Term of patent 14 years

To all whom it may concern:

Be it known that I, Albert S. Eggleton, a citizen of the United States of America, residing at Big Flats, county of Chemung, and State of New York, have invented a new, original, and ornamental Design for a Tumbler, of which the following is a specification, reference being had to the accompanying drawing, forming a part thereof.

The figure is a perspective view of a tumbler, showing my new design.

I claim:
The ornamental design for a tumbler, as shown.

ALBERT S. EGGLETON.
